UNITED STATES PATENT OFFICE.

FRANCIS M. TINKHAM, OF SPRINGFIELD, MASSACHUSETTS.

EXTENSIBLE SOFA-BED.

No. 823,649.

Specification of Letters Patent.

Patented June 19, 1906.

Application filed February 15, 1906. Serial No. 301,238.

To all whom it may concern:

Be it known that I, FRANCIS M. TINKHAM, a citizen of the United States of America, residing at Springfield, in the county of Hampden and State of Massachusetts, have invented new and useful Improvements in Extensible Sofa-Beds, of which the following is a specification.

This invention relates to the class of bedsteads, and particularly to that class known as "extension sofa-bedsteads," and is an improvement upon the construction shown in United States Letters Patent granted to me on September 8, 1903, numbered 738,582.

This invention has for its object to provide a structure in which a single piece of woven-wire fabric can be used, and adapted when extended to produce a level and uniform surface between the fixed or main framework and the extension part, and, further, it has for its object to provide means so that the extension part, together with the one-piece fabric, can be nested into the main frame, and, further, to provide means on the main framework for securely supporting the one-piece fabric when extended.

In the drawings forming part of this application, Figure 1 is a plan view of the sofa-bed in a folded position. Fig. 2 is an end elevation of the same. Fig. 3 is a sectional plan view of the bed in its extended position. Fig. 4 is an end elevation of the same. Fig. 5 is a detail end view of one of the longitudinal and supporting bracing members of the folding part secured to the main frame, taken on the line 5 5, Fig. 7, looking in the direction of the arrow. Fig. 6 is a view of the structure with some of the parts omitted, showing how the sectional members of the extension part are nested into the main frame. Fig. 7 is a partial view of the entire structure, showing the same in extended position, with the one-piece fabric a level surface, and also showing in dotted lines the path of movement of the jointed members.

Referring in detail to these drawings, *a* designates the angle-iron, which is rigidly secured to the legs *b* *b'* of the extensible frame, the legs *b'* being cut off, as shown, at the point *b* and engaging the horizontal web of the angle-iron *n*, as described below, as clearly shown in Figs. 6 and 7. The vertical web of the angle-iron *a* is secured to the legs of the extensible frame by means of rivets or other securing means, while to the horizontal

web is secured the woven-wire one-piece fabric *c*. It is of course understood that the end pieces *a* and *b* are duplicated at the opposite end of the frame. Pivotedly secured at each end of the extensible frame to the angle-irons *a* are extension-pieces *d*, the pivots connecting the irons *a* and pieces *d* being designated by *e*. Pivotedly secured to the pieces *d* by the pivots *f* are the angle-iron pieces *g*. These pieces *d* and *g* are adapted to be folded alongside of and into the main frame, as shown in Figs. 2 and 6.

The woven-wire fabric employed is one continuous piece extending from the left-hand side of the extensible frame, as shown in Fig. 4, to the extreme right-hand side of the main frame, the same being attached to the movable parts *a*, *d*, and *g*. A stationary or main frame composed of the pieces *i*, *j*, *k*, and *m* is pivotally connected to the extensible frame by levers *q* and *5* at the point 6, as described below.

n designates a piece of angle-iron, which is riveted to the legs *b* and *b'* by means of the rivets *n'* and with the horizontal web portion thereof extending inward, as shown, constituting a track for the movable frame. Rotatably secured in the angle-irons *m* are small antifriction-wheels *p*, as shown in plain view in Fig. 3 and side view in Figs. 2, 4, 6, 85 and 7. Pivotedly secured to the main-frame piece *j* at the points *j'* is a lever *q*, which has two offsets or earpieces *r* integral therewith and to which are pivotally secured the elbow-levers *s* and *t* by means of the rivets *u* and *v*. The levers *q* at both ends of the main frame *i*, *j*, *k*, and *m* are secured at their lower ends to a longitudinal rotatable brace rod or tube *q'*, which rotates with the levers *q* and in bearings in the piece *j*. Pivotedly secured to the elbow-lever *s* is a link *w*, which is pivoted at its upper end by means of the pivot *x* to the angle-iron *m*. The link *w* is pivoted to the elbow-lever *s* at *w'*. Pivotedly secured to the elbow-lever *t* by the pivot *y* is a link *z*, the opposite end of which is pivoted to the angle-iron *m* at the point 2. Also secured to the elbow-lever *t* and projecting therefrom is a foot-piece 3 for nesting the movable and main frames into each other, a corresponding foot-piece 4 being used for opening the structure, so as to form a bed of the ordinary width.

A slotted lever 5 is pivotally secured to the short leg *b'* of the movable frame at the point 6. This lever laps by the lever *q*. The slots 110

- 7 and 8 in these levers are adapted to receive the headed securing-rivets 9 and 10 for securing the inner ends of the levers *q* and 5 together and in sliding engagement. Rigidly 5 secured to the inner end of the vertical web of the extension part *g* is a brace-rod or tube 11 bent, as shown in Fig. 5, at the end and extending lengthwise of the structure and secured at its opposite end to the corresponding foldable extension-piece *g*. This brace-rod 11 has riveted to the lower side thereof at the curved part 11', as shown in Fig. 5, a foot-piece or bracket 12, which is adapted to rest upon the horizontal piece 12', which is 10 riveted to the under side of the part *m* when the structure is extended, as shown in Figs. 4 and 7. The piece 11 therefore acts as a post or supporting part for the outer end of the piece *d* when extended into horizontal position.
- 14 designates a connecting-piece between the parts *g* and *m*. This piece is riveted to the part *g* at 15 and pivotally connected to the piece *m* at 16, about which it turns when the bed is opened and closed, as shown in dotted lines in Fig. 7.
- 17 designates a tubular brace-rod extending lengthwise of the structure for rigidly securing together the outer ends of the extension-pieces *g*. (See Fig. 3.)
- 18 designates a stud on which the end of the angle-iron *n* rests when the structure is in closed position, as shown in Fig. 6, in order to keep the fabric of the main frame in a horizontal position. 19 also designates a stud on the horizontal web of the angle-iron *m* of the stationary or main frame and against which the end of the angle-iron *n* rests when the structure is open, as shown in Fig. 7, and 20 is for the purpose of preventing the extension-pieces *d* and *g* from accidentally folding should weight or pressure be applied to the outer end of the part *g*. It will be seen that when the extensible frame is slid off from the stationary or main frame *i*, *j*, *k*, and *m* that the extension-pieces *d* and *g* are supported in horizontal alinement by the pivot *e*, brace 11, and the link 14, the parts 11 and 14 transmitting the weight to the angle-iron *m* of the 25 main frame.
- 19' designates a brace-rod secured in the short legs *b'* for rigidly holding the same in spaced relation to each other. The longitudinal brace-rod 22 is also for rigidly securing the legs *b* in spaced relation, and the brace-rod 23 is for the same purpose. The corner brace-pieces 24, 25, and 26 are employed, as 30 shown, for rendering the structure firm and rigid.
20. (Shown in Fig. 2.) This movement draws the levers *w* and *s* together, as shown in Fig. 4, while at the same time the levers *t* and *z* are opened, as shown in this figure, and in opening the device the extension-pieces *d* 70 and *g* are pulled outward by the extensible frame by means of the levers *q* and 5 from the nested position shown in Fig. 2 to the open position in Fig. 4 and at the same time carrying with them the attached one-piece fabric *c*, thus giving a level and uniform surface to the fabric. 24 designates a guifling-piece for the angle-iron *n*, secured to the main frame, as shown in Fig. 2. It is understood that in extending the couch-bed the 80 main frame is pushed far enough to the left by the levers *q* and 5, so that the end of the angle-iron *n* is passed over and back of the holding-stud 19. When it is desired to close the bedstead, the operator places his foot on 85 the foot-piece 3 and with a downward pressure which is transmitted to the levers *t*, *q*, and 5 (the lever *t* pulling on the levers *q* and 5, which in turn is transmitted to the extensible framework,) slightly lifts the inner end 90 of the same so that the piece *n* is lifted free of the lug or stud 19, when with a continued downward pressure the extensible frame is drawn forward or toward the right, the horizontal web of the channel-iron *n* engaging 95 with the antifriction-roll *p* and passing over the same to a closing position, as shown in Figs. 2 and 6.
- The jointed members *d* and *g* are nested alongside of and into the main frame, as 100 shown in Figs. 2 and 7, the post 14 rotating through a semicircle. The braces 11 and 17 are shorter than the distance between the legs *k*, and therefore pass inside when the structure is folded. The jointed extension-pieces *d* and *g* rotate about the pivot-points *e*, *f*, and 16, as shown in dotted lines 30 in Fig. 7. It will be understood that the extensible frame *a*, *b*, *b'*, and *n* acts upon the pieces *d* and *g* through the levers *q* and 5 so 110 as to pull them into alinement when the bed is opened and pushes on them when the bed is folded. When the bed is open, the fabric is of course placed under the requisite tension when the auxiliary frame is locked behind 115 the lug 19.
- Having thus described my invention, what I claim, and desire to secure by Letters Patent of the United States, is—
1. In an extensible sofa-bedstead, the combination of a main frame, an extensible auxiliary frame, a one-piece fabric secured to said frames and capable of being partially folded alongside of and directly below the main frame.
  2. In an extensible sofa-bedslead, the combination of a main frame, an extensible auxiliary frame, a one-piece fabric secured to said frames and capable of being folded alongside of and into the main frame, means 125

for retaining the extensible auxiliary frame in extended position so that the one-piece fabric is placed under tension.

3. In a sofa-bedstead, an auxiliary frame, 5 extension-pieces secured thereto and comprising jointed portions, a one-piece fabric secured to the auxiliary frame and the jointed portions, and means for folding the jointed portions alongside of, and into the main 10 frame.

4. In an extension sofa-bedstead, a main frame, an auxiliary frame movable relative to each other in open and nested positions, a longitudinal rock-shaft pivoted in the main 15 frame, an oscillatory lever secured at each end of the rock-shaft and to the auxiliary frame, a pair of toggle-levers pivoted to each end of the main frame and to said oscillatory operating-lever, an articulated frame pivoted 20 to the main and auxiliary frames, one part of the articulated frame being adapted to fold against and into the main frame, a one-piece fabric secured to the main and auxiliary frames whereby when the bedstead is extended one pair of toggle-levers is closed and the other pair open, and whereby when the main and auxiliary frames are nested the other pair of toggle-levers is open and the other pair closed, as described.

30 5. In an extension sofa-bedstead, a main frame, an auxiliary frame movable relative to each other in open and nested positions, a longitudinal rock-shaft pivoted in the main frame, said rock-shaft being secured to the 35 main frame midway of its width, an oscillatory lever secured at each end of the rock-shaft and to the auxiliary frame, a pair of toggle-levers pivoted to each end of the main frame and to said oscillatory operating-lever, 40 an articulated frame pivoted to the main and auxiliary frames, one part of the articulated frame being adapted to fold against and into the main frame, a one-piece fabric secured to the main and auxiliary frames whereby when 45 the bedstead is extended one pair of toggle-levers is closed and the other pair open, and whereby when the main and auxiliary frames are nested the other pair of toggle-levers is open and the other pair is closed, as described.

60 6. In a sofa-bedstead, an auxiliary frame, a main frame secured thereto, said main frame having jointed portions, a one-piece fabric secured to the auxiliary frame and the 55 jointed portions, means for supporting the outermost one of the jointed portions, and means for folding the jointed portions on the main frame and at the same time folding the one-piece fabric into nested relation to the 60 two frames.

7. In a sofa-bedstead, a main frame, an auxiliary frame, a one-piece fabric carried by said frames, means on the main frame for preventing the main frame from sliding when in open position, said means consisting of a 65 lug secured to the main frame against which the auxiliary frame rests when in open position, and means for disengaging the auxiliary frame from the lug when the main and auxiliary frames are nested, as described.

8. An extensible sofa-bedstead, a main frame, an auxiliary frame, a one-piece fabric connecting the two frames, and means for nesting the two frames relative to each other, comprising an articulated frame connected 70 to the auxiliary and main frame and foldable into the main frame.

9. In an extensible sofa-bedstead, a main frame and auxiliary frame secured thereto, extension-pieces pivotally supported by the 80 main frame and connected to the auxiliary frame and carrying a fabric, and means for nesting the pivoted outer portion only of the extension-pieces into the main frame.

10. In an extension sofa-bedstead, an articulated frame secured to the main frame, an auxiliary frame pivotally secured to the main frame, a fabric secured to the articulated and auxiliary frames, means for nesting the articulated frame into the main frame, 85 said means consisting of a link pivoted to one member of the main frame and rigidly secured to a member of the articulated frame, whereby when the auxiliary and articulated frame are operated one member of the articulated frame will be nested into the main 90 frame.

11. In an extension sofa-bedstead, a main and auxiliary frame pivoted to each other, portions of the auxiliary frame supported on the main frame, a fabric secured to the auxiliary frame and pivoted portions of the main frame, and means for rotating a portion of the pivoted frame about a fixed point on the main frame, whereby a portion of the auxiliary frame is nested into the main frame.

12. An extensible sofa-bedstead, a main frame, an auxiliary frame, two sets of angle-irons included as a part of each of said frames, one set including jointed members and pivoted to the auxiliary and main frames respectively, whereby when the auxiliary frame is moved into nesting relation with the main frame the jointed members are carried below and into the main frame.

FRANCIS M. TINKHAM.
